WILLIAM SHOTEY, OF DETROIT, MICHIGAN

DEVICE FOR DRESSING GRINDING WHEELS

Application filed March 14, 1932. Serial No. 598,631.

The present invention pertains to a novel device for dressing the edges of a grinding wheel so that the latter may be inserted into the spaces between the teeth of a roughly 5 shaped broach for internal gears or between the teeth of spur gear and accurately form the involute outlines of the teeth. Accordingly, it is necessary to form concave involute surfaces on the grinding wheels in order that 10 these surfaces may form corresponding convex involute surfaces.

The invention embodies a fixed circular disk or arcuate member having a radius of curvature equal to the radius of the base 15 circle of the gear to be ground. Upon this member is mounted a frame lying tangential thereto and adapted to be turned on the member while maintaining its tangency. A given point on this frame therefore describes the involute curve of the base circle. The frame in fact is utilized as the holder for a tool which preferably has its point lying in the plane of tangency, so that this point also 20 describes the involute curve. When the 25 grinding wheel is brought against the point and the frame turned about the arcuate member, the point cuts the involute curve into the grinding wheel.

The invention also embodies means for 30 shifting the tool point from one position to another, these positions being such that involute surfaces are cut on both faces of the wheel, thus enabling the wheel to grind both sides of an inter-dental space at the same 35 time.

The invention is fully disclosed by way of example in the following description and in the accompanying drawing, in which—

Figure 1 is a side elevation of the device; 40 Fig. 2 is an end view, partly in section; Fig. 3 is a plan view;

Fig. 4 is a section on the line 4—4 of Figure 1;

Fig. 5 is a diagram illustrating the 45 involute movement of the dressing tool point;

Fig. 6 is a diagrammatic view showing the operation of the grinding wheel on an involute broach for internal gears; and

Fig. 7 is a similar diagram showing the 50 operation of the wheel on a spur gear.

Reference to these views will now be made by use of like characters which are employed to designate corresponding parts throughout.

In Figures 1, 2 and 3 is illustrated a suitable base member 1 carrying a stub shaft 2 on which are mounted a pair of congruent spaced disks 3 of equal circumferences. A pin 4 is preferably passed through both disks and into the base member to prevent turning 55 of the disks.

On the shaft 2 and between the disks 3 is pivotally mounted an arm 5 having in its upper end a slot 6 extending beyond the circumference of the largest disks which the 65 device will accommodate, as will presently appear. Roller bearings 7 are mounted on a stud 8 which lies loosely in the opening, and these bearings lie directly over the disks 3.

A hollow rectangular frame 9 lies between the disks 3 and bearings 7 and has its sides resting upon the disks and engaged by the bearings. A screw 10 adjustable in the upper end of the arm 5 bears upon the stud 8 75 and is adapted to clamp the bearings 7 against the frame 9 for a purpose which will presently appear.

A boss 11 extends laterally from the frame 9, and on the boss is rotatably mounted a cap 80 12 having a finger 13 extending therefrom at right angles to the disks 3. A dressing tool 14 is mounted transversely in the finger 13 and is adapted to be adjusted lengthwise by a locknut 15. A key 16 is secured diametri- 85 cally within the cap 12, as shown in Figure 4, and enters a diametrical slot 17 in the outer end of the boss 9. A disk 18 is seated in the other end of the boss, and a spring 19 joins the disk to the key 16, whereby the cap is 90 yieldably held in a fixed position on the boss 11.

The grinding wheel 20 to be dressed by the tool 14 is designed to enter the inter-dental spaces of a broach for internal gears to 95 accurately finish the tool. Consequently, it is desired that the opposite faces of the wheel 20 be shaped at their edges in concave involute fashion, as indicated by the numeral 21, in order to grind the convex involute 100

faces. In being dressed, the wheel is driven from a spindle 20' on which it is mounted.

In order to enable accurate initial setting of the frame 9, a locating or centering tool is adjustably mounted in a vertical slot 22 formed in the base member 1. This device comprises a casing 23 guided in the slot and containing a spring pressed pin 24 adapted to enter a correspondingly shaped opening 25 in the side of the frame as illustrated in Figures 2 and 3. The casing 23 cannot slip in any direction in the horizontal plane because of its mounting in the base member 1 and maintains its elevation after the pin 24 is inserted in the frame, whereby the frame and the tool are maintained in a fixed position while the bearing 7 is being clamped upon the frame. The pin is then withdrawn from its opening and held in the withdrawn position by a finger 26 fixed thereto and adapted to engage the end wall of the casing 23.

In the operation of the device, the wheel 20 or the base 1 is so adjusted that the periphery of the wheel 20 passes through the plane of tangency of the frame 9 to the disks 3. The point of the tool 14 lies in the same plane and therefore describes an involute curve with reference to the disks 3 when the frame 9 is turned on the disks without slippage. The frame 9 is turned by swinging the arm 5 which may be grasped at its upper end. The contacting surfaces of the frame 9 and disks 3 may be roughened in order to avoid slippage, and if the bearings 7 are clamped tightly upon the frame by means of the screw 10, they will turn before the frame slips on the disks 3.

It will be seen in Figures 1 and 3 that the point of the tool 14 lies at one side of a plane which is normal to the plane of tangency of the plane 9 to the disks 3. This normal plane is midway between the curved edges 21 and represents a plane which bisects an interdental space radially. One edge 21 is dressed by slowly swinging the arm 5 to the same side of the normal plane while the wheel 20 is being rotated.

In order to set the tool for dressing, the other edge 21, the pin 24 is first returned to its opening 25 and the cap 12 is pulled outwardly against the spring 19 until the key 16 is out of the slot 17. The cap is then turned through an angle of 180°, and the key is reinserted in the slot. This turning of the cap swings the tool around to the other side of the wheel 20 and in such a manner that both the old and new positions of the tool point are symmetrical with respect to the normal plane. The pin 24 is now withdrawn and the remaining edge 21 is dressed by swinging the arm 5 to the same side of the normal plane in the manner already described.

The circumference of the disks 3 repre-

sents the base circle of the broach or gear to be ground. The tool point, in moving on this circle in the manner described, therefore describes the involute curve of the circle. For another size of broach or gear, the disks 3 are replaced by another pair of disks having the circumference of the base circle of that broach or gear.

In Figure 5 the operation of the tool is illustrated diagrammatically to show the involute movement of its point as the frame 9 moves from its initial position A to another position B while held tangential to the disks 3 and without slipping relatively thereto. It will be understood also that the disks 3 need not be complete circles but require an arcuate edge only where contacted by the frame 9 in the movement of the latter.

Figure 6 illustrates the dressed wheel in the operation of finishing the involute faces of a stub tooth involute broach 30 for forming internal gears. The periphery 31 of the wheel extends substantially to the base circle as indicated. Figure 7 shows the wheel employed in finishing the teeth of a spur gear 32, and in this case the periphery of the wheel extends slightly beyond the base circle.

In the use of the tool for either a broached or a spur gear, the periphery 31 is required to cut an arc of a circle. The periphery therefore requires a transverse concavity having the radius of the arc to be cut, and this formation may be imparted by a suitable dressing means of any type known in the art.

Although a specific embodiment of the invention has been illustrated and described, it will be understood that various alterations in the details of construction may be made without departing from the scope of the invention, as indicated by the appended claims.

What I claim is:—

1. A device for dressing grinding wheels comprising a base, an arcuate member carried thereby, a rigid arm pivoted to said base at the center of said arcuate member, a clamping member adjustably mounted in said arm, a tool holder clamped tangentially upon the periphery of said arcuate member by said clamping member, and a dressing tool carried by said holder, said tool holder having its working point disposed in the plane of tangency of said holder to said arcuate member.

2. A device for dressing grinding wheels comprising a base, an arcuate member carried thereby, a rigid arm pivoted to said base at the center of said arcuate member, a clamping member adjustably mounted in said arm, a tool holder clamped tangentially upon the periphery of said arcuate member by said clamping member, and a dressing tool carried by said holder, said tool holder having its working point disposed in the

plane of tangency of said holder to said arcuate member, said point being disposed at one side of a plane normal to said plane of tangency, said point being adjustable from 5 one to the other of two positions symmetrical with respect to said normal plane.

3. A device for dressing grinding wheels comprising a base, an arcuate member movably carried thereby, a rigid clamping member 10 pivoted to said base at the center of said arcuate member, a tool holder clamped tangentially upon the periphery of said arcuate member by said clamping member, and a dressing tool carried by said holder, said tool 15 being offset axially from said arcuate member.

4. A device for dressing grinding wheels comprising a base, an arcuate member carried thereby, a clamping member pivoted to 20 said base at the center of said arcuate member, a tool holder clamped tangentially upon the periphery of said arcuate member by said clamping member, a dressing tool carried by said holder, and a centering pin engageable with said tool holder for locating 25 the same during adjustment of said clamping member.

In testimony whereof I affix my signature.
WILLIAM SHOTEY.
